UNITED STATES PATENT OFFICE.

ADELBERT A. HENDERSON, OF WILKINSBURG, PENNSYLVANIA.

LIFT-BRIDGE.

1,352,450.

Specification of Letters Patent. Patented Sept. 14, 1920.

Application filed November 21, 1918. Serial No. 263,504.

To all whom it may concern:

Be it known that I, ADELBERT A. HENDERSON, a citizen of the United States, residing at Wilkinsburg, in the county of Allegheny and State of Pennsylvania, have invented 5 certain new and useful Improvements in Lift-Bridges, of which the following is a specification.

The prime object of the present invention is to provide a new and improved 10 bridge structure of the movable or lifting bridge type designed for spanning navigable waters, and of a character capable of sustaining heavy loads passing over the bridge.

15 Further objects of the present invention are to provide, at all times and without any interruption whatever during navigable stages of water, an opening of any required clearance for water traffic; to provide, at all 20 times and without any interruption whatever, an unobstructed or uninterrupted passageway for all traffic passing over the bridge, and a construction permitting the bridge to be raised, lowered, and supported 25 at any intermediate elevation between certain fixed limits, conformably with the varying stage of water.

In the accompanying drawings which illustrate applications of my invention,

30 Figure 1 is a side elevational view of a bridge constructed in accordance with my invention, showing the normal position of the bridge;

Fig. 2, a view similar to Fig. 1 showing 35 the bridge raised;

Fig. 3, a side elevational view showing a plurality of tilting spans on each side of the vertical movable span, with the bridge raised;

40 Fig. 4, a side elevational detail view particularly showing the manner of supporting the ends of the tilting spans nearest the shore;

Fig. 5, a view similar to Fig. 4 showing a 45 modified construction;

Fig. 6, a sectional view taken on the line 6-6 of Fig. 1; and

Fig. 7, a detail side elevational view showing 50 the manner of supporting the adjacent ends of the tilting and vertically movable spans.

Referring to the drawings and first to the form of bridge shown by Fig. 1, 2 designates a navigable stream and 3 abutments of any approved construction located

on opposite sides of the stream. As illustrated, piers 4 are so disposed as to provide a central channel, although the number and arrangement of the piers, as well as the mechanism employed for raising and lowering 60 the bridge structure, may be varied.

A desirable construction in accordance with my invention includes, a central vertically movable span 5 and two end-tilting spans 6. Each of the spans is formed with 65 a roadway, the level of which is indicated by the numeral 7.

The power means for raising and lowering the movable parts of the bridge may comprise any suitable means, as screws, lifting cables, etc., familiar to those skilled in bridge construction. As shown, I employ 70 hydraulic cylinders or jacks 8 partly located within and partly projecting from the piers 4.

75 The manner of mounting the adjacent ends of the central and tilting spans on an upper plate member 9 of the hydraulic operating structure 8 is particularly shown by Fig. 7, and the preferred manner of supporting the opposite or abutment ends of the 80 tilting spans is illustrated by Fig. 4.

As shown, separated blocks or shoes 11 and 10 fixedly secured to plates 9 are employed for the respective points of support 85 of the tilting spans and the vertically movable span, said points of support being indicated by the numerals 13 and 12.

14 designates a block mounted on and secured to an abutment 3, and 15 a rocker- 90 post extending upwardly from block 14. In this construction, the point of support 16 is located above the surface of the roadway 7 and the point of support 13 of the opposite end of the tilting span below the roadway 95 floor, the point of support 16 being preferably placed at an elevation midway between the lowest and highest positions assumed by the point of support 13 at the pier. This construction provides the minimum of horizontal motion for the points of supports 13 and 16 as the span moves from one extreme position to the other.

100 It is also preferable in this construction to make the vertical distance of the point of support 16 above the roadway floor equal the vertical distance of the point 13 below said floor.

105 Operating the tilting spans under the construction described results in a horizontal movement of the two terminals of roadway 110

at the ends of the respective end spans in a direction toward each other, thus equally dividing the horizontal movement between the ends of said spans when the span is 5 raised to its highest position. The movement of said tilting spans causes each to rotate about its two points of support 13 and 16 and causes the point of support 13 to move in a vertical plane and the point of 10 support 16 in an arc of a circle about the point of support of the rocker-post 15.

If preferred, the rocker-posts 15 may be omitted and the masonry carried up sufficiently to have the point of support 16 rest 15 thereon. Under this latter construction, the point of support 13 will move in a vertical plane and the point of support 16 in a horizontal plane.

In the form of Fig. 5 I have shown a 20 construction in which the point of support 16' for the abutment end of the tilting span is placed below the roadway 7' and mounted on roller bearings 17. In this instance, the point of support for the tilting span at 25 the pier will also be below the roadway floor. To equally divide the horizontal movement of the two terminals of the roadway under this last construction, the vertical distance of the points of support below 30 the roadway at the respective ends of the spans should be developed along the lines described in considering the construction of the form of Fig. 1. In cases in which the points of support for the tilting spans are 35 placed below the roadway, the point of support at the pier will move in a vertical plane and the point at the abutment in a horizontal plane, the span being designed to rotate about the two points when it is tilted. 40 In the form of Fig. 3 I have shown a plurality of tilting spans 6' on each side of the central vertically movable span 5' and an additional number of piers 4' and lifting mechanism 8', otherwise the construction is 45 substantially the same as shown and described in the form of Fig. 1.

In all of the forms illustrated and as preferred, the points of support 12 for the vertically movable span 5 are disposed below 50 the roadway floor and it will be understood that in raising and lowering the bridge said points of support are moved in a vertical plane.

In operation, the channel or central span 55 5 is moved up and down by raising and lowering its two points of support 12 substantially equally and simultaneously, and the end spans 6 are tilted by raising and lowering the respective points of support 13 60 at the piers, equally and simultaneously with the points of support 12. The points of support for the tilting spans at the abutments have no vertical motion, or at most, a negligible quantity.

65 The advantage this type of movable

bridge possesses over a fixed bridge to connect any two given points, is that it maintains a passageway of required clearance for water traffic, obtainable in a fixed bridge only when constructed at the maximum elevation assumed by the movable bridge, and whenever the said movable bridge occupies a position lower than its maximum elevation it provides a roadway of less grade than that furnished by the fixed bridge. 70 The advantage it possesses over all other types of movable bridges is that it is operated without any interruption of either the land traffic or water traffic. 75

What I claim is:

1. In a bridge structure, a vertically movable span, an adjacent tilting span, positively operating means for simultaneously effecting a vertical movement of the adjacent ends of said spans, and means for permitting a lateral movement of the opposite end of said tilting span. 80

2. In a bridge structure, a vertically movable span, an adjacent pivotally mounted tilting span, positively operating means for simultaneously effecting a vertical movement of the adjacent ends of said spans, and means for permitting a lateral movement of the opposite end of said tilting span. 90

3. In a bridge construction, a central vertically movable span, adjacent tilting spans, positively operating means for effecting a vertical movement of the adjacent ends of the central and tilting spans, and means for permitting a lateral movement of the opposite ends of the tilting spans. 95

4. In a bridge construction, a central span having its points of support movable in a vertical plane, adjacent tilting spans having their points of support adjacent the points of support of the central span movable in a vertical plane, means for effecting a vertical movement of said points of support, and means for permitting a lateral movement of the points of support of the opposite ends of the tilting spans. 105

5. A lift bridge including a roadway floor, a vertically movable lift-span having its points of support disposed below the floor, adjacent tilting spans, with the points of support for the ends of the tilting spans nearest the vertically movable span disposed in a horizontal plane below the floor and with the points of support of the opposite ends disposed in a different horizontal plane, and positively operating means for moving the spans. 115

6. A lift bridge including a roadway floor, a vertically movable lift-span having its points of support disposed below the floor, adjacent tilting spans, with the points of support for the ends of the tilting spans nearest the vertically movable span disposed below the floor, and with the point of support for the ends of the tilting spans at 125 130

the abutments disposed above the floor, and positively operating means for moving the spans.

7. A lift bridge including a roadway floor, a vertically movable lift-span having its points of support disposed below the floor, adjacent tilting spans, with the points of support for the ends of the tilting spans nearest the vertically movable span disposed below the floor, and with the point of support for the ends of the tilting spans at the abutments disposed above the floor, said

last mentioned point of support for each tilting span being substantially the same vertical distance above the floor as the distance of the opposite point of support is below the floor, and positively operating means for moving the spans.

In testimony whereof I affix my signature in presence of two witnesses.

ADELBERT A. HENDERSON.
